UNITED STATES PATENT OFFICE.

GOODRICH Q. LEWIS, OF WHEATON, ILLINOIS, ASSIGNOR TO WILLIAM H. MINER, OF CHAZY, NEW YORK.

RAILWAY DRAFT-GEAR.

1,255,187.

Specification of Letters Patent.

Patented Feb. 5, 1918.

Application filed October 18, 1915. Serial No. 56,436.

To all whom it may concern:

Be it known that I, GOODRICH Q. LEWIS, a citizen of the United States, residing at Wheaton, in the county of Du Page and State of Illinois, have invented a certain new and useful Improvement in Railway Draft-Gears, of which the following is a full, clear, concise, and exact description, reference being had to the accompanying drawings, forming a part of this specification.

This invention relates to improvements in railway draft gears.

The object of the invention is to provide a gear for railway draft riggings having a high friction capacity under buff and high spring capacity only, under draft.

Another object of the invention is the provision of a draft gear having the qualities above enumerated so arranged as to permit the use of a horizontal yoke.

In the drawing forming a part of this specification, Figure 1 is a vertical, longitudinal sectional view of a draft rigging showing my improvement in connection therewith. Fig. 2 is a horizontal, longitudinal sectional view of the structure illustrated in Fig. 1 and taken on the line 2—2 of the latter. Figs. 3 and 4 are transverse, vertical sectional views taken on the lines 3—3 and 4—4 of Fig. 1. And Fig. 5 is a perspective view of one of the stop castings employed with my construction.

In said drawing, 10—10 denote the center or draft sills to which are secured the counterpart stop castings A—A, each casting A being provided with a pair of upper and lower rear stop shoulders 11—11, a pair of upper and lower front stop shoulders 12—12, an upper intermediate shoulder 13 and a lower intermediate shoulder 14, intermediate shoulders 13 and 14 being vertically spaced and also out of alinement, as clearly appears from Fig. 5. Mounted between the draft members is a stationary friction shell 15, the latter having an integral front follower section 16, the latter at the lower end being provided with lateral extensions or shoulders 17—17. On its lower side, the cylinder 15 is provided with longitudinally extending side flanges or webs 18—18, the rear edges of which are flush with the rear end of the cylinder 15 and are adapted to abut the lower, intermediate shoulders 14. The front follower

16 engages the front stops 12—12, as will

be apparent, and the upper intermediate stops 13 engage the rear face of the follower 16 at the top thereof. In this manner, the friction cylinder 15 is prevented from forward movement by engagement with the four stops 12—12 and is prevented from rearward movement by the two upper stops 13—13 and the two lower, intermediate stops 14—14, thereby holding the friction cylinder stationary.

On account of the construction, as above described, it is apparent that the friction cylinder may be inserted between the sills from below without interference with any of the stops. Mounted within the friction cylinder 15 is a plurality of friction shoes 19, wedge 20 and anti-friction rollers 21. At the rear of the friction shell and normally in engagement therewith, is a movable spring front follower 22, the latter having an annular extension 23 on its front face which fits within the friction cylinder 15 and is guided by the latter. Between the follower 22 and the shoulders 24 on the friction shoes is a preliminary spring 25 and the friction shoes, wedge rollers, preliminary spring and follower 22 are held together in assembled relation by means of a retaining bolt 26. A rear follower 27 normally engages the rear stops 11 and between said follower and the follower 22 are vertical, twin arranged main springs 28—28, each of the latter comprising an outer and an inner coil, the two sets of springs being separated by means of a spacer 29, the latter also serving to limit the amount of compression of said springs, as will be understood and as clearly appears from Fig. 5. The upper set of stops on each casting are spaced from the lower set of stops and thereby provide a longitudinally extending channel or groove within which is adapted to be received one arm 30 of a horizontal yoke, the forward ends of the yoke arms being keyed to a draw-bar 31, as clearly appears in Fig. 2. As will be apparent, the yoke is supported and guided on the upper flanges of the lower stops 11, 12 and 14. In assembling the draft rigging, the yoke is first placed in position by inserting the same endwise, then the friction shell 15 with the friction mechanism preliminary spring and follower 22 assembled therewith is inserted from the bottom of the sills, then the rear follower 27 and finally the springs and spacer 29. The friction shell, followers, 110

springs and elements within the friction shell are then supported by means of a saddle plate 32 bolted to the lower flanges of the draft sills 10.

5. In operation, upon inward movement of the draw-bar, the wedge and friction shoes are moved inwardly relatively to the stationary shell 15, which movement is resisted at first by the preliminary spring 25. After 10 the preliminary spring has been compressed, further inward movement of the friction shoes is resisted by the twin sets of main springs acting through the follower 22. It will therefore be seen that upon buff, 15 the action is graduated and reaches an ultimate high friction capacity. In draft, the follower 22 is held stationary by the shell 15, and consequently none of the friction elements comes into play, but the rear follower 27 is pulled forwardly by the yoke, 20 thus compressing the springs 28 and thereby providing a heavy spring action only, in draft.

I claim:

25. 1. In a draft rigging, the combination with a relatively short stationary shell, friction elements coöperable therewith under buff, and twin arranged springs arranged to resist movement of said friction elements 30 under buff, of a horizontal yoke acting to compress only said springs, under draft, said springs being insertible and removable while the shell and friction elements are in position.
35. 2. In a draft rigging, the combination with draft sills, stop castings secured to the inner faces of said sills, each of said castings being provided with spaced upper and lower, front and rear stops and also intermediate 40 stops, of a friction shell insertible between said castings and adapted to engage the front stops thereof, said shell remaining stationary in both buff and draft, friction elements coöperable with said shell, a yoke, the

arms of which pass between said shell and 45 said castings, said arms being guided between the sets of upper and lower stops, and spring means coöperating with said friction elements.

3. As an article of manufacture, a stop 50 casting for draft riggings, said stop casting having spaced upper and lower sets of front and rear stop shoulders, and spaced upper and lower stop shoulders intermediate said front and rear stop shoulders, said intermediate stop shoulders being out of vertical alinement whereby to permit the insertion of a friction shell vertically between two of said stop castings when the latter are in position, the spaced upper and lower front, 60 rear and intermediate stop shoulders permitting the employment of a horizontal yoke slidably mounted therebetween.

4. A stop casting for draft rigging and the like having spaced upper and lower rear 65 stop shoulders, spaced upper and lower front stop shoulders, and spaced upper and lower stop shoulders intermediate the front and rear stop shoulders, the intermediate stop shoulders being out of alinement with each 70 other, the longitudinal space between the upper and lower sets of stop shoulders forming a guide for a horizontally slidable member.

5. In a draft rigging for railway cars, the combination with draft members having 75 stop castings permanently secured thereto, of a stationary friction shell mounted between said stop castings and insertible vertically therebetween, friction elements coöperable with said shell under buff only, main 80 springs at the rear of said shell, and a horizontal yoke slidably mounted between said friction shell and said stop castings.

In witness that I claim the foregoing I have hereunto subscribed my name this 27th 85 day of Sept., 1915.

GOODRICH Q. LEWIS.
